CLAIM

We claim the ornamental design for a ink container, as shown and described.

DESCRIPTION

FIG. 1 is a top, front, and right side perspective view of a ink container showing our new design;

FIG. 2 is a front elevational view thereof, the rear being a mirror image;

FIG. 3 is a right side elevational view thereof, the left side being a mirror image;

FIG. 4 is a top plan view thereof; and,

FIG. 5 is a bottom plan view thereof.
